UNITED STATES PATENT OFFICE.

BENJAMIN F. CAHN, OF CINCINNATI, OHIO.

DESIGN FOR A WALL-FIXTURE FOR COUNTERS.

SPECIFICATION forming part of Design No. 22,589, dated July 4, 1893.

Application filed June 8, 1893. Serial No. 477,018. Term of patent 3½ years.

To all whom it may concern:

Be it known that I, BENJAMIN F. CAHN, a citizen of the United States, and a resident of Cincinnati, in the county of Hamilton and 5 State of Ohio, have invented a certain new and useful Design for Wall-Fixtures for Counters, of which the following is a specification.

My invention is a new and original design for wall fixtures for counters, the leading features of which are the end pilasters and columns, the entablature apparently supported thereby, and the intermediate columns apparently supporting the arch upon the top of which rests the central portion of the architrave, and the space below the arch and between the columns decorated with reflecting scroll work, as shown in the accompanying drawings, in which—

Figure 1 is a front elevation of one half of 20 the fixture. Fig. 2 is a vertical transverse section of the same.

The lower or sideboard portion A may be of any approved design now in common use. At each end of the sideboard portion are paneled pilasters B, which extend some distance up above the center portion and are mounted with molded caps b. The abacus of the pilaster caps support two plain columns or shafts C, which are of highly polished material. 25 These columns are surmounted by carved capitals c, above which, at each end, is a molded abacus c' upon which the entablature rests. Upon the abacus c' rests a plain cap piece D, which supports four short columns d. The columns are surmounted with carved capitals and extend up to the molding d', which is the lower finish of the cornice. Above this molding, on each end, is a pilaster cap E, the plain body of which is provided 30 with a bevel edged reflecting panel e, and the upper portion finished with an ovolو molding e', which apparently supports the top molding e' of the cornice. Above the molding e' and underneath the upper molding of the 35 cornice, extending the entire length of the sideboard, is a number of dentals e'.

The frieze F is recessed back of the upper and lower moldings d' and d'', which moldings are returned at the center of the fixture,

and between the ends and the center, and 50 between the outwardly projecting portions formed by the return of the molding, are short columns f, similar to the columns d, and surmounted by similar capitals. There are six of these small columns in the center, and 55 two between the returned portions of the molding between the end pilaster and the center columns, the columns being equally spaced.

Between the columns in the frieze are 60 raised bevel edged reflecting panels g, and the returned moldings underneath the intermediate columns have carved corbels h, which rest against the plain surface of the wall fixture or molding of the frame which 65 surrounds the reflecting panel I.

Between the cornice and the molding d', at the center of the fixture, is a bracket J, the lower portion of which rests upon the returned molding d', which is the abacus of the central short capitals of the columns f. The bracket curves outwardly to the upper edge of the cornice, and the curved under surface is formed of ribbed or carved reflecting surfaces.

In the spaces beneath the cornice are arches k, in which are fitted the semi circular panels k', which are also bevel edged reflecting surfaces, and between the center and end arches are triangular shaped recesses fitted 80 with cathedral glass ornaments.

Resting upon the center portion of the sideboard are two columns L, having molded necks and carved capitals l, each capital being surmounted with a molded abacus l', 85 from the top of which springs an arch m. The front of the arch m is enriched by carved scroll work m'. The space between the two central columns is enriched with scroll work N of cathedral glass.

What I claim as new, and desire to secure 90 by Letters Patent, is—

The design for wall fixtures for counters, substantially as herein shown and described.

BENJAMIN F. CAHN.
